UNITED STATES PATENT OFFICE.

ABRAHAM COOPER, OF NEW YORK, N. Y.

DESIGN FOR A CHAIN-LINK.

48,023.

Specification for Design.

Patented Oct. 26, 1915.

Application filed August 7, 1915. Serial No. 44,334. Term of patent 3½ years.

To all whom it may concern:

Be it known that I, ABRAHAM COOPER, a citizen of the United States, residing in the borough of the Bronx, New York city, county of the Bronx, and State of New York, have invented a new, original, and ornamental Design for Chain-Links, of which the following is a specification, reference being had to the accompanying drawing, forming part thereof.

Figure 1 is a view of one side of the

chain-link showing my new design, which is repeated on the obverse side of said chain-link. Fig. 2 is an end view thereof.

I claim:

The ornamental design for a chain-link, as shown.

ABRAHAM COOPER.
